UNITED STATES PATENT OFFICE

93,275

DESIGN FOR AN AUXILIARY GAME TABLE OR SIMILAR ARTICLE

Margaret W. Karpe, Los Angeles, Calif.

Application January 20, 1934, Serial No. 50,461

Term of patent 3½ years

To all whom it may concern:

Be it known that I, MARGARET W. KARPE, a citizen of the United States, residing at Los Angeles, in the county of Los Angeles, and State of California, have invented a new, original, and ornamental Design for an Auxiliary Game Table or Similar Article, of which the following is a specification, reference being had to the accompanying drawing, forming a part thereof.

The figure is a perspective view of the article showing my new design.

I claim:

The ornamental design for an auxiliary game table or similar article, as shown.

MARGARET W. KARPE.
